[57] CLAIM

The ornamental design for a bottle, as shown and described.

DESCRIPTION

FIG. 1 is a perspective view of a bottle showing my new design;

FIG. 2 is a top plan view on an enlarged scale;

FIG. 3 is an elevational view thereof;

FIG. 4 is an elevational view looking from the left of FIG. 3; and

FIG. 5 is a bottom plan view thereof.

The sides opposite those shown are substantially the same in appearance as the respective sides shown.
